DESIGN FOR A TRUNDLE TOY

John T. Armbruster, Niagara Falls, N. Y.

Application December 8, 1945, Serial No. 124,551

Term of patent 3½ years

(Cl. D34—15)

To all whom it may concern:

Be it known that I, John T. Armbruster, a citizen of the United States of America, residing at Niagara Falls, in the county of Niagara and State of New York, have invented a new, original, and ornamental Design for a Trundle Toy, of which the following is a specification, reference being made to the accompanying drawing, forming a part thereof.

Fig. 1 is a perspective view of the trundle toy embodying my design;

Fig. 2 is a front view of the trundle toy shown in Fig. 1;

Fig. 3 is a top plan view of the trundle toy shown in Figs. 1 and 2.

I claim:

The ornamental design for a trundle toy, substantially as shown.

JOHN T. ARMBRUSTER.
